(57) **CLAIM**

The ornamental design for a connector holder, as shown and described.

DESCRIPTION

FIG. 1 is a perspective view of our design for a connector holder.

FIG. 2 is a front view of the connector holder of FIG. 1.

FIG. 3 is a rear view of the connector holder of FIG. 1.

FIG. 4 is a left side view of the connector holder of FIG. 1.

FIG. 5 is a right side view of the connector holder of FIG. 1.

FIG. 6 is a top view of the connector holder of FIG. 1; and, FIG. 7 is a bottom view of the connector holder of FIG. 1. The broken lines shown throughout these figures depict environmental subject matter only and form no part of the claimed design.
